(57) **CLAIM**

The ornamental design for a platform with independently slidable jaws, as shown and described.

DESCRIPTION

FIG. 1 is a top perspective view of a platform with independently slidable jaws.

FIG. 2 is bottom perspective view thereof.

FIG. 3 is a top perspective view thereof with environment.

FIG. 4 is a front view thereof (rear view being mirror image).

FIG. 5 is left-side view thereof (right-side view being mirror image).

FIG. 6 is a top view thereof; and,

FIG. 7 is a bottom view thereof.

The broken line showing of parts of the drawings is included for the purpose of illustrating use and environment, and forms no part of the claimed design.
